UNITED STATES PATENT OFFICE.

GEORGE POTSTADA, OF SAN FRANCISCO, CALIFORNIA.

ROTARY WEFT-MEASURER.

1,164,959.

Patented Dec. 21, 1915.

Application filed January 27, 1914. Serial No. 814,698.

To all whom it may concern:

Be it known that I, GEORGE POTSTADA, a citizen of the United States, residing at San Francisco, in the county of San Francisco and State of California, have invented a new and useful Rotary Weft-Measurer, of which the following is a specification in such full and clear terms as will enable those skilled in the art to construct and use the same.

10 This invention relates to a rotary measuring device for looms and its object is to precisely determine the length of a thread to be woven into a strip of cloth by the shuttle or weft carrier.

15 This invention is especially intended to be used in connection with the weaving of cloth from a pair of large spools of yarn at each side of the strip of cloth in the loom, the weft threads being cut automatically to a length 20 precisely twice the width of the strip of cloth in the loom, the object being to dispense as far as possible with the use of small spools of yarn and bobbins in the shuttle or weft carrier.

25 Additional objects of the invention will appear as the description proceeds.

An embodiment of the invention is shown in the drawing in which the same reference numeral is applied to the same portion 30 throughout, but I am aware that there are many modifications thereof.

Figure 1 is a side elevation of the complete apparatus looking toward the frame of the loom, Fig. 2 is a plan view of the complete apparatus, Fig. 3 is a vertical sectional view of the measuring device, also illustrating a portion of the frame of the loom, Fig. 3^a is a diagrammatic view illustrating the position of the spools of yarn and the appearance of the weft thread after it has been woven into the cloth, Fig. 4 is an elevation of the measuring apparatus looking in a direction opposite to that of Fig. 1, Fig. 5 is a back view of the rotary thread measuring 45 wheel, Fig. 6 is an enlarged view of the upper portion of the thread measuring wheel illustrating the position of the knife when cutting the thread, the cam operating the knife being indicated in dotted lines, Fig. 7 is a view 50 partly in section of the thread measuring finger and the periphery of the disk which carries it, a portion of the thread measuring finger being broken away irregularly to show the means on the rotary wheel 47 for lifting

the thread out of the notch in the finger 48, 55 the plane of section being at right angles to Fig. 8, Fig. 8 is a plan view of the thread measuring finger, Fig. 9 is a plan view of a portion of the top of the measuring device illustrating the position of the thread and 60 the parts related thereto, when a fresh length of thread is to be carried through the shuttle, Fig. 10 is a side elevation of the casing within which the measuring device works, the measuring wheel and cover plate being 65 removed for purposes of illustration, Fig. 11 is a plan view of a portion of the top of the measuring device illustrating the position of the thread when the loop end is to be carried through the shed, and Fig. 12 is a bottom 70 plan view of the thread holding slide.

This measuring apparatus is assembled at opposite ends of a single shaft below and parallel to the lay of the loom, one measuring device being right-handed and the other left-handed, but otherwise one is a duplicate of the other so that only a description of one 75 will be given.

The device comprises a flat casing 1 having a projecting boss 2, which boss affords a 80 journal bearing for a shaft 3. The casing is suspended from the lay of the loom 4 by means of a bracket 5 depending therefrom and said boss is held in a fixed position by means of the set screw 6. Mounted within 85 the casing (see Fig. 10) is a cam 7, the boss 2 being extended within said casing to afford a bearing for the cam to rotate on as indicated at 8, a set screw 9 being provided to secure said cam tightly in place when it has been 90 once adjusted.

Extending through the back of the casing the cam is provided with an arm 10, which arm is provided with threads which mesh with the threads of the worm 11. This worm 95 11 is carried by a small shaft 12 in a bracket 13 on the side of the casing, a collar 14 preventing said shaft from moving longitudinally when once it is placed in the bracket 13. The object of this adjustment is to enable the 100 cam to be moved back and forth the necessary amount to cause the knife to cut off the exact length of thread.

At the top of the casing there is a notch 15, said notch being for the purpose of affording the weft carrier admittance to the thread holding fingers. At the side of this notch there is secured a plate 16 which has a

shoulder 17 to precisely determine the position the thread will occupy when drawn out of the casing and when being otherwise operated upon by the parts engaging it, as will appear later.

At the side of the casing there is a light spring 18 which bears upon the disk 19 to prevent the thread from becoming entangled and is released by the measuring finger.

- 10 At the top of the casing there is a segmental slide 20 which slide has a hook eye 21 and two fingers 22 and 23 at its middle portion. The slide has two slots 24 and 25 and is held in place in the casing by means of two short bolts 26 and 27, the pressure of said bolts upon the slide being regulated by means of a spring 28 within each of the threaded caps 29 and 30. At the back of the slide there is a notch 31 for a purpose to be described presently. Secured to the underside of the slide is the spring knife 33 and the spring thread holder 34. The spring knife 33 has one portion turned up as indicated at 35 to form the cutting plate and passed between the two fingers 22 and 23 and it has another portion 36 turned up to enter the slot 31 to hold the thread holder 34 in the proper position and to prevent the thread from passing off the rotary disk by any chance.
- 30 The thread holder carries a steel shoe 37 on its underside which bears on the ring cam 38 secured to the measuring disk. The fingers 22 and 23 are for the purpose of holding the thread in the proper position to be picked up by the thread carrier each time it is presented to the measuring disk, but one time the thread carrier picks up the end of the loop, while upon its return it picks up the fresh end thereof, so that the position of the fingers must be shifted to present the proper end of the thread to the thread carrier. This shifting is accomplished by means of the two levers 40 and 41. These levers are pivoted to the casing at 42 and 43 respectively and they have depending portions 44 and 45, the surfaces of which are so shaped as to shift the slide from one position to the other upon each rotation of the disk, a pin 46 carried by the disk causing the slide to be shifted as required.

It will be observed that the thread carrier C is indicated in dotted lines in Fig. 11 under one portion of the thread and with its jaws in engagement with the cut-off loop.

- 55 At this time the thread has been measured and is ready to be released when the carrier is thrown through the shed. In Fig. 9 the carrier is indicated in a position to engage the fresh end of the loop to draw the weft through the shed, Fig. 11 being the position succeeding that of Fig. 9 and after the engagement of the loop has occurred. When the thread has been carried from the position indicated in Fig. 9 through the shed and is beaten up into the cloth it occupies

the position illustrated in Fig. 2, in which the disk 47 is to such a position as to bring the measuring finger or looper 48 opposite the fingers 22 and 23. In order to insure the retention of the thread by the measuring finger it is provided with a notch 49, while the finger is also grooved as indicated in Fig. 8 at 50 to enable a small finger A carried by the periphery of the disk 47 to lift the thread out of the notch 49 when the finger recedes at the end of the loop.

The finger is held in place on the disk by means of the screw 51 which passes through a slot 52 in the thread measuring finger and it is held normally in the position shown in Fig. 5 by means of the spring 53 bearing upon it. The lower end of the finger rests upon the cam 7 and has its travel determined thereby, the adjustment of said cam determining the length of time the finger will act upon the loop. In order to insure the lifting of the thread to the proper position to be caught by the finger 48, a cam rim 55 is screwed on the side of the disk as the latter rotates. On the front the disk is provided with the ring cam 38 screwed thereto, which cam (see Fig. 1) is so shaped as to lift the thread holder and thread against the underside of the slide 20 from the point D to the point C during which time a cam 56 on the outside of the disk lifts the knife 33 and cuts the thread. Immediately after the thread is cut and from C to B, the cam 38 slightly releases the thread holder, but at the same time it holds the same tight enough to retain the end of the thread against the finger 22 until the loop end has been taken away, whereupon to insure against the possible loss of the end under the finger 22 the cam is raised from B to A', thereby more tightly securing the end under the finger 22 while as soon as the disk goes to A' which is the position corresponding to that of Fig. 9 the cam is slightly released from A' to A'', thereby enabling the thread carrier to take the end away after which the cam is reduced in size from A'' to D to insure a wide space for the insertion of the thread under the fingers 22 and 23 at the proper time.

The form of weft and the supply therefor is indicated in Fig. 3^a in which 60 represents the first weft thread which is taken from the large spool 61, 62 representing the first weft thread to be taken from the spool 63, these threads alternating in position while the two last threads 64 and 65 are shown in the measured and cut-off position ready to be carried through the shed. In order to prevent the thread from becoming entangled with the several parts of the machinery, a guide eye 66 is secured on the back side of the casing. The disk is keyed to the shaft 3 at 68 and in order to prevent the key from loosening a small set screw 69 is 130

provided. The operating levers 40 and 41 extend into notches 40' and 41' respectively of the slide 20. The end of the casing is provided with a flat cover 70 held in place by means of the pin 71 extending into a hole 72 in the bottom of the casing 1, the upper portion of the cover being provided with two springs 73 to frictionally engage the inside of the casing 1 and hold the cover in place.

10 In operation the yarn is threaded through the hook 21, a loose end being left hanging. The measuring device at the opposite end of the lay is threaded up in the same manner, whereupon the loom is started. In 15 the operation of the loom the shaft 3 is rotated and as said shaft is rotated the finger 48 will catch the loose end of the yarn (note Fig. 2) and will draw it forwardly. When 20 the yarn end happens to be too short to form a loop, it will be cut off and left in the position shown in Fig. 9, whereupon the carrier will come forward and pull the end through the shed, leaving said end upon its release at the opposite end of the lay. As soon as the 25 yarn end has been carried to the opposite end of the lay the finger 48 will come around again and engage the yarn (see Fig. 2) and form the loop drawing the yarn down until the finger 48 slips off the cam 7, whereupon 30 the knife will cut the yarn and the loop end (see Fig. 11) will be moved into the position to be caught by the carrier on its next trip to that end of the lay, the several 35 operations being repeated in the same order thereafter.

Having thus described my invention what I claim as new and desire to secure by Letters Patent of the United States, is as follows, modifications within the scope of the 40 claims being expressly reserved:

1. A rotary weft measurer comprising the combination of a slide having yarn holding fingers, means to shift the slide to present opposite ends of the yarn in a given place, 45 a revolute disk, a looper carried by said disk to engage the yarn and draw the loop, means to disengage said looper from the yarn when the loop has been made the desired length, and means to cut the yarn adjacent the holding fingers.

2. In a rotary weft measurer, the combination of a slide, yarn holding fingers carried thereby, a revolute disk, a looper carried thereby to draw a loop in the yarn, 55 means to release said looper from the yarn when the loop has been made of sufficient length, and means to shift said slide to present alternately the loop ends and the spool ends of the yarn to a weft carrier.

60 3. In a weft measurer, the combination of a casing, a slide carried thereby, yarn holding fingers carried by said slide, a revolute disk, a looper carried by said disk to engage the yarn and form a loop therein, means to disengage said looper from the

yarn when the loop is of the desired length, means to cut the yarn adjacent the fingers, and means to shift said slide to present alternately the loop ends and the spool ends of the yarn to a weft carrier.

4. A rotary weft measurer comprising the combination of a casing, a slide carried thereby, yarn holding fingers carried by said slide, a revolute disk in the casing, a looper carried by the disk to engage the 75 yarn and form a loop therein, adjustable means to cause said looper to be disengaged from the yarn when the loop is of the desired length, means to cut the yarn adjacent the holding fingers, and means to shift said slide 80 to present alternately the loop ends and the spool ends of the yarn to a weft carrier.

5. In a rotary weft measurer, the combination of a casing, a slide carried thereby, yarn holding fingers carried by said slide, a knife 85 adjacent said fingers, a revolute disk having a cam thereon to operate said knife, a looper carried by said disk to engage the yarn and form a loop therein, means to disengage said looper from the yarn when the loop is of the 90 desired length, whereupon said cam causes the knife to cut said yarn between said fingers, and means to shift said slide to present alternately the loop ends and the spool ends of the yarn to a weft carrier.

6. In a weft carrier, the combination of a casing, a slide carried thereby, two yarn holding fingers and a hook eye on said slide, a revolute disk, a looper carried by said disk to engage the yarn and form a loop 100 therein, means to disengage the looper from the yarn when the loop is of the desired length, means to adjust the position of disengagement of said looper to determine the exact length of the loop, a knife extending 105 between the yarn holding fingers, a cam carried by the disk to cause the knife to cut the yarn when the loop has been formed, and means to shift said slide to present alternately the loop ends and the spool ends of 110 the yarn to a weft carrier.

7. In a weft measurer, the combination of a casing, a slide carried thereby, two yarn holding fingers carried by said slide, a revolute disk, means carried by said disk to 115 shift the said slide, a looper carried by said disk to engage the yarn and form a loop therein, two levers secured to the casing for shifting the position of the slide to present alternately the loop ends and the spool ends 120 to a weft carrier, a knife to cut the yarn adjacent the fingers, and a cam carried by the disk to operate said knife.

8. A rotary weft measurer comprising the combination of a casing, a slide carried 125 thereby, yarn holding fingers and a hook eye on said slide, a revolute disk, a looper carried by said disk to engage the yarn and form a loop therein, means to disengage said looper from the yarn when the loop is 130

of the desired length, means to cut the yarn between the yarn holding fingers, a cam carried by the disk to press the yarn holder into engagement with said fingers and having a depression therein to permit the partial release of the yarn after it is cut and another depression therein to permit the full release of the yarn when the spool end thereof is to be picked by the weft carrier, and means to shift the slide to present alternately

the loop ends and the spool ends of the yarn to a weft carrier.

In testimony whereof I have hereunto set my hand this 20th day of January A. D. 1914, in the presence of the two subscribed ¹⁵ witnesses.

GEORGE POTSTADA.
